CLAIM

The ornamental design for a cleaning implement, as shown and described.

DESCRIPTION

FIG. 1 is a perspective view of the cleaning implement.

FIG. 2 is a top plan view thereof.

FIG. 3 is a bottom plan view thereof.

FIG. 4 is a right side elevational view of the cleaning implement, the left side elevational view being a mirror image thereof; and,

FIG. 5 is a right end elevational view of the cleaning implement, the left end elevational view being a mirror image thereof.
